1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, UNITED STATES PATENT OFFICE.

EDWARD W. BULLOCK AND ALTON P. SLADE, OF ROCHESTER, NEW YORK, ASSIGNEES
TO GLEASON WORKS, OF ROCHESTER, NEW YORK, A CORPORATION OF NEW YORK.

GEAR-GRINDING MACHINE.

Application filed July 5, 1924. Serial No. 724,356.

This invention relates to a gear grinding machine, and while applicable generally to grinding different types of gears, it has reference more particularly to generating-type machines used in producing gears having lengthwise curved teeth, sometimes called spiral or circular tooth gears.

One purpose of the invention is to afford a practicable, efficient mechanism for properly correlating the movements of an annular rotary grinding wheel and a gear blank, while obtaining a relative generating movement between said parts during the grinding operation.

Another purpose of the improvement is to provide mechanism that will operate automatically to dress a grinding member at predetermined intervals, or after a predetermined number of tooth operations are completed, and in this aspect, the invention is intended especially for automatically dressing an annular rotary grinding wheel so that no attention from the operator is required in keeping the grinding wheel in proper condition.

A further purpose of the invention resides in the provision of automatic mechanism for separating the tool and blank after a blank is completed, by effecting a relative movement between said parts to inoperative position to permit removal of the blank, and in this as well as certain other aspects, the invention has utility in connection with gear cutting as well as gear grinding machinery.

The invention also includes various other improvements and refinements having to do with the perfection of automatic gear making machinery, all of which will appear clearly from the following description when read in conjunction with the accompanying drawings, the novel features being pointed out in the claims following the specification.

In the drawings:

Figure 1 is a plan view of a machine incorporating a preferred embodiment of the invention;

Figure 2 is a side elevation, partially in section, of the mechanism illustrated in Figure 1;

Figure 3 is a longitudinal vertical sectional view with parts in elevation;

Figure 4 is a horizontal sectional view taken substantially on line 4-4 of Figure 3;

Figure 5 is an enlarged end elevation, partially broken away, showing the carrier 55 for the blank support, the grinding wheel, and housing for the dressing mechanism;

Figure 6 is a transverse vertical sectional view with parts broken away, and partially in section;

Figure 7 is an enlarged plan view of the grinding wheel and blank in operative position, with parts in section;

Figure 8 is a horizontal sectional view on line 8-8 of Figure 29;

Figure 9 is a horizontal sectional view on line 9-9 of Figure 30, illustrating the grinding wheel and a portion of the drive to the dressing mechanism;

Figure 10 is a detail sectional view on line 10-10 of Figure 9;

Figure 11 is a diagrammatic elevation of part of the gearing shown in Figure 9;

Figure 12 is an elevation of the dressing mechanism;

Figure 13 is a similar view with parts broken away, and showing the drive gearing;

Figure 14 is an enlarged side elevation, illustrating a portion of the means for operating the dressing wheel;

Figure 15 is a sectional view on line 15-15 of Figure 14;

Figure 16 is a sectional view on line 16-16 of Figure 14;

Figure 17 is a sectional view on line 17-17 of Figure 15;

Figure 18 is a sectional view on line 18-18 of Figure 15;

Figure 19 is a sectional view on line 19-19 of Figure 13;

Figure 20 is a sectional view on line 20-20 of Figure 19;

Figure 21 is a sectional view on line 21-21 of Figure 13;

Figure 22 is a sectional view on line 22-22 of Figure 2;

Figure 23 is an enlarged sectional view of the cam, and its cooperating parts, that control the movements of the grinding wheel bed, the parts appearing in normal position;

Figure 24 is a similar view showing the position of said parts after the completion

of a gear blank, when acting to withdraw the grinding wheel bed to inoperative position;

Figure 25 is a sectional view on line 25—25 of Figure 24;

Figure 26 is a sectional view on line 26—26 of Figure 25;

Figure 27 as a diagrammatic view of the cam;

10 Figure 28 is an enlarged view of a portion of the cam showing the switch member in normal position;

Figure 29 is a similar view showing the switch member moved so as to withdraw the grinding wheel bed to inoperative position;

15 Figure 30 is an end elevation of the machine, showing the mechanism for controlling feeding and dressing of the grinding

20 wheel;

Figure 31 is a similar view enlarged, partially broken away, illustrating the automatic stop mechanism and parts which it controls;

25 Figure 32 is an enlarged plan view with reference to Figure 30, and showing the parts in normal position;

Figure 33 is a similar view showing the parts when operated to feed and dress the 30 grinding wheel;

Figure 34 is a horizontal sectional view taken generally on line 34—34 of Figure 31;

35 Figure 35 is an enlarged side elevation of part of the cam mechanism shown in Figure 30;

The invention is applicable to machines other than that hereinafter specifically disclosed, and except where necessarily restricted, the several features of the invention may be adapted to gear machinery of various types, such for instance as where the blank is operated on by either a grinding 70 or a cutting tool, and also to both generating and non-generating types of machines.

The disclosure of this application is intended merely as an example of a preferred embodiment of the invention, and preferably includes a tool in the form of a rotary, annular grinding member or wheel, rotating through a groove or tooth space of a gear blank, while a generating relationship is maintained between the grinding wheel and blank. This is preferably accomplished by mounting the gear blank on a support arranged on a movable carrier, which has a back and forth motion to impart to the blank a translatory movement. During such translatory movement, the blank is rotated about its axis by means of a gear segment fixedly connected to the gear blank support and rolling upon a stationary gear segment.

The result of this combined translatory and rotary movement of the blank support is to roll the gear blank past the grinding wheel during the grinding operation of the latter. The gear blank is rolled first in one direction and then in the other to complete a tooth space operation, following which the grinding wheel is automatically withdrawn from the gear blank to permit indexing the latter. To accomplish this, the grinding wheel is mounted on a bed which is intermittently moved away from the gear blank and returned after completion of the indexing operation.

A dressing mechanism is provided for the grinding wheel, and acts automatically at predetermined intervals, after every fourth tooth operation, for instance. At the completion of the predetermined interval, and during an indexing operation, the grinding wheel is automatically fed toward the blank and then dressed, thereby truing or restoring the operative surfaces of the grinding wheel.

Upon completion of a blank, or after all the teeth of the blank have been operated upon by the grinding wheel, the machine is automatically stopped and at the same time a throw-out mechanism automatically functions to separate the blank and tool mechanism to a relatively inoperative position, so as to permit removal of the blank by the operator without any manual adjust-

ment or positioning of the grinding wheel. After the operator places another blank on the support, he has only to start the machine, following which the throw-out mechanism automatically functions to restore the grinding wheel and blank to normal or operative relationship, and the operation is repeated in the sequence already described.

Similar reference numerals throughout the different views refer to the same parts, and in the structure shown, 1 designates the base of the machine. 2 is the intermittently reciprocating bed on which the grinding member support is mounted, as will herein-
15 after be described in detail, and 3 is the blank support or spindle to which the necessary movement is imparted to roll the blank over the grinding wheel during operation of the latter. The description immediately following refers to the mechanism for carrying and giving the required rolling movement to the blank support 3.

Blank support and mechanism controlling its generating movement.

The gear blank support 3 is arranged within the arms 4 of a head 5 which is adjustable on a table 6, see Figures 7 and 47, by means of the adjusting pinion 7 and rack 8, the rack 8 being fixed to the table 6 while the adjusting pinion 7 is carried by the head 5. The table 6 and parts just described, including the blank support, are mounted upon a movable carrier 9, which preferably has an oscillating motion in the curved ways 10. The necessary motion is imparted to the carrier 9 by a link 11, see Figures 3 and 6, which is connected to a crank on the driven shaft 12, such oscillatory motion of the carrier serving to impart to the gear blank α , see Figure 7, the translatory motion for moving it past the grinding wheel. During this translatory movement, the gear blank is rotated about its axis by means of a gear segment 13, see Figures 1 and 47, which has a fixed relation to the gear blank support during the grinding operation, and rolls upon a stationary gear segment preferably composed of two sections 14 and 15, see Figures 48 and 49. As the carrier 9 oscillates, it carries with it the gear blank support, and the segment 13 which has a fixed relation to the gear blank support. Thus, segment 13 is caused to roll on the stationary segment sections 14, 15, and thereby turn the blank support about its axis. In this fashion, the gear blank is given a rolling movement past the grinding wheel during operation of the latter, corresponding to the movement of the gear blank rolling bodily upon a crown gear, a tooth of which is represented by the grinding wheel.

In the practical operation of the machine, it is desirable to permit a slight yielding

movement of the stationary gear segment as the moving segment rolls thereon, and it has been found that the best results are obtained by making the stationary gear segment in two sections, which are independently yieldable, the rolling gear segment 13 cooperating successively with the segments 14, 15. The structure of the sectional gear segments is shown in Figures 6, 48 and 49. Each segment 14, 15 is mounted upon a slide 16 which is movable in a suitable guideway, and is held in normal position by a spring 17. This arrangement permits a slight yielding of the stationary gear segment, and at the same time overcomes any binding or chatter of the parts, by keeping the direction of yielding movement of the stationary segment more nearly in line with or closer to the point of engagement with the rolling gear member than if the gear members 14, 15 were integral. The description now to follow pertains to the grinding member and its supporting and controlling mechanism.

Grinding wheel and controlling parts.

The tool mechanism of the disclosed embodiment comprises a rotary annular grinding wheel 20, and in order to index the gear blank after completion of each tooth, provision is made for effecting a relative separation of the gear blank support and grinding member to permit indexing. This may be accomplished as in the structure shown by mounting the grinding wheel on a bed that is intermittently moved away from and returned toward the blank support.

It is essential to maintain the grinding wheel true, and in proper and accurate relationship to the blank so that the various teeth will be ground uniformly, and this is brought about by a dressing mechanism including dressing wheels cooperating with the opposite sides and edge of the grinding wheel, and functioning automatically to dress such surfaces after a predetermined number of tooth operations, according to the requirements of the particular work. It is also necessary to feed the grinding member slightly toward the gear blank preparatory to the dressing operation, and this is accomplished by mounting the grinding wheel on a support that is automatically slidable on the bed above mentioned toward the gear blank support just before the dressing operation takes place.

The grinding wheel 20, see Figure 43, is mounted on a spindle 21 in a manner that will be described later, and the spindle 21 is in turn journaled in a support 22, see Figures 2, 3 and 8, which is slidable on the bed 2 toward the blank support, the support 22 and with it the grinding wheel being advanced slightly toward the blank support by the following mechanism immediately preceding the dressing operation, and while

90

95

100

115

120

125

130

the blank and tool mechanism are separated.

Referring to Figures 2, 8, and 30 to 33, the support 22 is operatively associated with an operating shaft by a nut 23 which is engaged by the screw 24, the latter being journalled in a bracket 25 attached to the bed of the machine. The screw 24 is part of a shaft which has keyed thereto a worm wheel 26 engaged and driven by an intermittently operated worm 27. The worm 27, see Figures 2, 8, 30 and 37, is arranged within a housing 28 and mounted on the upper end of a shaft 29 which carries fixed thereon at its lower end a ratchet wheel 30. 31 is a spring controlled pawl secured on a pawl carrier 32 and cooperating with the ratchet wheel 30 to turn the same when moved. 33 is a link connecting the pawl carrier 32 with the arm 34, which is pivoted at 35 and carries a projection or roller 36 that is engaged and operated successively by cams 37, arranged on an intermittently rotating cam wheel 38. The cam wheel 38 is actuated in a manner to be described later, and the cams 37 are adjustably arranged thereon in such manner and the parts so timed that after every fourth tooth operation and during the succeeding indexing operation, a cam 37 will engage roller 36 and swing the arm 34, thereby rocking the pawl carrier from the position shown in Figure 32 to that shown in Figure 33, and thus turning the screw 24 and advancing the grinding wheel support on its bed a proper distance to allow for operation of the dressing mechanism and consequent truing, or restoring of the grinding wheel, to proper form. After the grinding wheel has been advanced toward the blank support as just described, it is automatically dressed by the following mechanism.

The dressing mechanism, which is shown in detail in Figures 12 to 21, and will be described more fully hereinafter, includes a pinion 40, see Figures 9 and 12, which is oscillated intermittently and thereby operates the dressing mechanism to true the operative surfaces of the grinding wheel. The pinion 40 is engaged and driven by a ring gear 41 which in turn is operated by a pinion 42 on a driven spindle 43. The driven spindle 43 carries a pinion 44 fixed thereon which is engaged and operated by a reciprocating rack 45. The rack 45 is secured at the upper end of a shaft 46, see Figure 30, which is adjustably connected to the hollow shaft 47 by an adjustable telescopic connection illustrated in Figure 36, the two parts of the shaft being held in adjusted relationship by the thumb screw 48.

The hollow shaft 47 which operates the rack 45, see Figures 10, 30 and 35, is connected at its lower end to an arm 49, see Figure 35, which in turn is pivotally mounted

at 50 on an extension 51 of the arm

34. The arm 49 carries a projection or roller 52 which, when arm 34 is in the position shown in Figure 33, engages and is operated by a camway 53 formed on the continuously rotating cam wheel 54, fixed upon the driven shaft 12. The rotation of shaft 12 is so timed with reference to the operation of the other parts of the machine that after a given number of tooth operations, four in the present instance, arm 49 is swung into the path of the camway 53 on cam wheel 54, the latter then engaging the roller on arm 49, and continued movement of the cam wheel 54 will then raise and lower successively the arm 49 and with it the shaft 47, thus imparting reciprocatory motion to rack 45 and through the parts already described, causing operation of the dressing mechanism. The detailed construction of the dressing mechanism will now be described.

Dressing mechanism for grinding wheel.

The dressing mechanism is generally similar to that disclosed in copending application Serial No. 659,547, filed August 27, 1923, although the present structure contains certain improved features, and is combined with automatic instrumentalities for operating it after a given number of tooth operations.

Referring to Figures 12 to 21, the pinion 40 previously mentioned is mounted upon one end of a shaft 60, which is suitably supported in a housing 61 that supports the dressing mechanism. The shaft 60 carries at its opposite end a pinion 62 that engages a rack 63. Said rack 63 is formed integral with the rack 64, which engages and operates the pinion 65, the latter in turn oscillating the curved rack 66. The rack 66 engages and operates the pinion 67, see Figure 13, which cooperates with and reciprocates the oppositely arranged slides 68. Each slide 68 carries a dressing wheel 69 for cooperation with one of the oppositely inclined surfaces 70 of the grinding wheel, said dressing wheel 69 being mounted and operated in the following manner.

Referring to Figures 13 to 18, the dressing wheel 69, which is of spherical formation, is rotatively mounted on bearings 71 in a support 72, the support being rotated continuously during reciprocating movement of the slide 68 in the following manner. The support 72 includes an arbor 73 which has formed thereon a ratchet 74, while 76 are oppositely disposed dogs cooperating with said ratchet and mounted respectively on the bevel gears 77. The gears 77 are engaged by and turned in opposite directions by the bevel gear 78, which is integrally associated with a spur gear 79 cooperating with a stationary rack 80.

As the slide 68 moves in one direction or

the other, carrying with it the dressing wheel and its support, the gear 79 is moved along with reference to the stationary rack 80 and thereby turned, first in one direction and then in the other. This causes opposite turning of the gears 77 and the dogs 76 carried thereby being oppositely arranged, a continuous rotation of the dressing wheel holder 72 is effected. The relatively stationary rack 80 is mounted on a stationary slide 81 to permit the necessary lateral movement of the rack 80 as the slide 68 reciprocates.

The dressing wheel 69 cooperates with the opposite surfaces 70 of the grinding wheel as just described, and at the same time the edge 82 of the grinding wheel is dressed by the dressing wheel 83 in the following manner. Dressing wheel 83 is mounted on an arbor that is oscillated from the rack 63 by means of the gear segment 84, gear 85 and pinion 86 in the manner disclosed in said co-pending application, and since the construction of this portion of the drive to dressing wheel 83 does not differ from that of the application referred to, it is unnecessary to disclose said parts further in this application. From the mechanism just described, it will be understood that after a given number of tooth operations, an automatic operation occurs which first advances the grinding wheel slightly and then causes the three dressing wheels to function and engage the opposite sides and edge of the grinding wheel, truing the latter and preparing it for further operation on the blank. No attention from the operator is required in the control of the dressing mechanism, the entire sequence of movements of the machine being automatic from the time it is started until the blank is completed.

Main drive.

Referring to Figures 2, 3 and 4, the machine is controlled from an electric motor 90 and motor shaft 91 to which are fixed pulleys 92, while 93 is a belt leading from said pulleys 92 around tightener pulleys 94 to the pulley 95 on the grinder wheel spindle, see Figure 43. Thus, the grinding wheel is driven continuously, and the necessary movements of the grinding wheel for indexing are permitted by the belt drive from motor shaft 91 to the grinding wheel spindle.

The shaft 91 carries a bevel pinion 96, see Figure 4, engaging bevel gear 97 on shaft 98. The shaft 98 drives shaft 99 through suitable change gears 100, see Figures 2 and 4, while shaft 99 carries a worm 101, driving the worm wheel 102 on the main or driven spindle 12, see Figure 3. The driven spindle 12 effects the necessary rolling movement of the gear blank support through link 11 already referred to, and carries fixed thereon the cam wheel 54 already described, which

imparts the required movement to the dressing mechanism. The previously mentioned cam wheel 38 carries a ring gear 104, see Figures 30 and 31, which is operated by the interrupted gear 105, the latter being in turn intermittently driven from the gear 106 fixed on the driven spindle 12, see Figures 3 and 31.

The gear 106 carries two teeth 107 which engage the interrupted gear 105 and moves it a quarter of a turn once for each rotation of the gear 106. The gear 106 rotates once during each tooth operation, and the mechanism provides for four such operations between each pair of cams 37. Upon the completion of every fourth tooth operation, one of the cams 37 engages roller 36 on the arm 34 and through the parts already described, advances the grinding wheel on its bed and dresses the grinding wheel while the blank indexing movement is taking place. Thus, by the time the grinding wheel is returned to grinding relationship with the blank, the grinding wheel will have been completely dressed and accurately restored to its initial and proper form for cooperation with a tooth on the blank.

Control for bed of grinding wheel.

In the structure shown, the relative separation of the blank and tool mechanism to permit indexing the blank is effected by moving the bed on which the grinding wheel is mounted away from and toward the blank support. Referring to Figure 3, this is accomplished by a projection 110 or pin carried by the bed 2 and engaging a cam 111, which is fixedly mounted on the driven spindle 12, so that for each rotation of the latter, the bed is moved away from the blank and returned after completion of the indexing operation. It is desirable upon completion of a blank to automatically separate the grinding wheel and blank to inoperative relationship, to permit removal of the blank by the operator without requiring a manual separation, as usual in this class of machinery, and the throw-out mechanism by which this is brought about will now be described.

The cam 111 which controls the in-and-out movement of the bed 2 is so constructed that its effective contour can be changed so as to withdraw the grinding wheel bed a greater distance than required for indexing, and establish such an inoperative relationship between the grinding wheel and blank support as to permit removal of the blank and setting of another blank, and this change in the effective contour or relation of the cam 111 is brought about automatically upon completion of a predetermined number of tooth operations.

One mechanism for effecting this result embodies an oscillatory switch device 120,

75

80

100

105

110

115

120

125

130

see Figures 23, 24, 28 and 29, which is mounted on an oscillatory arbor 121. When the switch device 120 is in the normal position illustrated in Figure 28, rotation of the 5 cam 111 withdraws the bed 2 far enough to permit indexing and then returns it, the projection 110 following the contour of the cam, as shown in dotted lines in Figure 28. Upon completion of all the teeth on a blank, the 10 switch device 120 is automatically shifted to the position shown in Figure 29, causing the projection 110 to follow the path there shown in dotted lines, and thereby causing the bed to be withdrawn from the blank support 15 to inoperative position. This movement of the switch device 120 to the position shown in Figure 29 takes place immediately prior to stopping the machine, the entire operation being automatically governed in the following manner.

The arbor 121 carries a gear segment 122, see Figures 23 and 24, which is engaged by a rack 123. The rack 123 is fixedly carried by a sleeve 124 that is engaged and operated 25 by a yoke 125 pivoted at 126 upon a stationary support so as to swing about a horizontal axis, see Figure 23. The operation is preferably effected by weight-controlled means, and to this end the yoke 125 carries 30 a weight 127 which is pivotally connected to the yoke so as to swing about a vertical axis 128, see Figures 23, 24 and 34, the weight being held in normal position on the yoke by the spring 129, see Figure 34. The 35 weight 127 normally occupies the position shown in Figure 23, where it is held upwardly, and when released in the manner to be described presently, it drops to the position shown in Figure 24, operating the yoke 125 correspondingly and thereby through 40 the sleeve 124 and cooperating parts, shifting the switch device 120 to throw out the grinding wheel bed to inoperative position.

The weight 127 is held in its uppermost 45 position by the arm 130 carried thereby and resting on an abutment 131, and is moved laterally or about the pivot 128 to permit it to fall, by means of an operating member 132, see Figure 31, said operating member 50 being pivoted at 133 and carrying an anti-friction roller 134. Roller 134 is engaged by an anti-friction roller 135 on the switch 136 which controls the electric motor 90, and 55 137 is a controlling device pivoted at 138 and acting when operated to move and release the weight 127, and through it the switch device of the cam 111. At the same time the electric switch 135 is moved to open the motor circuit and stop the machine. 60 The controlling device 137 is governed by an automatic stop mechanism which functions after a predetermined number of tooth operations preferably as follows.

140 designates a ratchet wheel that is 65 turned for each tooth operation on the blank

by means of an operating dog 141 carried on a pivoted arm 142. The latter is operated by a plunger 143 that is controlled by a cam 144 fixed on the driven spindle 12 and engaging the plunger 143 once during each rotation of the driven spindle. When the ratchet wheel 140 is turned through the predetermined distance, a pin 145 carried thereby engages the controlling device 137 as shown in Figure 31, causing the operation 70 just described. Immediately following this, the ratchet wheel 140 is returned to its initial position by a controlling spring 146, see Figure 34, ready for operation on another blank. The return movement of the ratchet wheel 140, see Figures 31 and 34, is cushioned by a stop pin 147 carried thereby 80 and engaging a yieldable stop 148 which is cushioned by the spring 149. The parts are in normal or initial position when the pin 147 is in engagement with stop 148.

During the normal operation, the ratchet wheel is held against return movement by a locking dog 150 carried by the controlling device 137 and normally engaging the teeth 90 of the ratchet wheel. In the position illustrated in Figure 31, the actuating member has been moved partially by pin 145, showing the initial movement of the parts as the automatic stop mechanism functions. Further movement of the controlling device 137 from the position shown in Figure 31 releases weight 127 and also opens the motor circuit through the switch 135, and the upper end of the controlling device 137 will 100 then have moved laterally far enough to engage a recess 151 in the locking member 152, which is actuated by a spring pin 153. This serves to hold the controlling device 137 and its dog 150 disengaged from the ratchet wheel 140 so as to permit the latter to return to its initial position. The locking member 152 holds said parts in such retracted position until the machine is restarted, whereupon the locking member is released and the parts are automatically returned to normal 110 position ready for another operation, and at the same time the weight controlled means for governing the cam switch is reset in the following manner.

Upon reclosing the motor circuit, the driven spindle 12 again commences to rotate. A cam 160 then engages a spring plunger 161, see Figure 34, moving said plunger and with it a resetting plate 162, see Figures 31 120 and 34, which elevates the locking member 152 against the action of the spring pin 153 and permits the controlling device 137 to return to its normal position. Coincidently with the movements of the parts just described, the weight 127 is elevated from the position shown in Figure 24 to that shown in Figure 23, until the arm 130 re-engages the abutment 131. This is brought about by 125 an arm 163 fixedly connected to the yoke 125 130

and carrying a projection or roller 164 which lies in the path of a cam 165 fixed to the driven spindle 12, as shown in Figures 23 and 24. Thus, as the driven spindle 12 rotates, the cam 165 operates the yoke 125 to its normal position, restoring the weight 127 and with it the parts 132 and 135 to their normal positions, ready for operation upon a second gear blank, whereupon the sequence of movements just described is repeated.

Indexing mechanism.

The indexing mechanism for turning the gear blank support through a distance of one tooth after each tooth operation, is somewhat similar to that disclosed in copending application Serial No. 715,390, filed May 23, 1924. In general, this mechanism includes an index wheel 170 which is normally in locked relationship with the rolling gear segment 13 and adapted to be unlocked at predetermined intervals to permits relative turning of the gear blank support with reference to the rolling segment. This is accomplished through a locking means that alternately engages and disengages the index wheel, and it is highly desirable at times to afford some way of adjusting the blank support and index wheel with reference to the remaining parts of the index mechanism or with reference to the rolling segment.

This is brought about in the present structure in a novel and extremely efficient manner, by providing for adjustment of the index wheel and the locking member cooperating therewith, with reference to the remaining parts of the index mechanism, and without disturbing the relation of the locking member and index wheel. To this end, there is employed a pivoted lever 171 similar in function to that disclosed in the copending application referred to above, said lever being held in normal position by a spring plunger 172 engaging an anti-friction roller 173 at the rear end of the lever. The lever 171 has mounted thereon a slide 174, and the slide 174 carries a locking dog 175 which engages the index wheel 176.

The slide 174 is held in adjusted relation on the lever 171 by means of clamping bolts 177. 178 is a manually controlled adjusting worm cooperating with worm gear teeth 179 on the edge of the slide 174. To adjust the gear blank support and index wheel with reference to the remaining parts, the clamping bolts 177 are loosened, and by turning the worm 178, the slide 174 is given a movement with reference to the lever 171, and carries with it the locking dog 175, the index wheel, and the blank support. A fine adjustment can thus be readily obtained, and when the blank support is in the desired position, the clamping bolts 177 are tightened to hold the adjustable slide and locking

dog in such position. 180 are adjustable stops for cooperation with opposite sides of an extension on the locking dog, said stops being used to determine the position of the locking dog with reference to opposite faces 70 of a tooth space.

Mounting for grinding wheel.

Referring to Figure 43, the grinding wheel is mounted upon the spindle 21, which is journaled in a tapered radial bearing 190 arranged in close proximity behind the grinding wheel, while 191 designates a thrust bearing at the small end of the tapered bearing 190. 192 is a collar carried by sleeve 193 which is adjustably mounted on the spindle to engage the thrust bearing 191. 194 is a nut threaded in the housing to engage the collar 192, and adjustable toward said collar to take up wear or vary the pressure between collar 192 and bearing 191. The sleeve 193 is held in adjusted position on the spindle by a locking collar 195 splined on the spindle and held in locked relationship to the sleeve 193 by a nut 196, while 197 is a spring 90 acting to retract the locking collar 195 when nut 196 is released. With this arrangement, any wear on the spindle is readily and completely taken up by adjusting sleeve 193 to draw the spindle toward the small end of 95 the tapered bearing 190, and when the proper adjustment is obtained, sleeve 193 can easily be locked in place securely, while nut 194 determines the pressure relation between bearing 191 and collar 192. The 100 thrust bearing 191 and collar 192 are surrounded by an oil chamber 200, see Figures 22 and 43, oil being supplied to said chamber through a cup 201 and passage 202, while 203 is a transparent closure through which the oil level can be observed. The oil chamber 200 is curved at its outer portion as indicated in Figure 43, and the oil being thrown into contact with said curved surface by the rotating collar 192, is thence conducted by such curved surface to the tapered spindle bearing on one side and to the bearing 110 for sleeve 193 on the opposite side.

The spindle 21 is driven by the aforementioned belt 93, see Figure 6, which passes over the tightener pulleys 94, the latter being arranged in a pivotally mounted frame 199, while 198 is a spring-actuated tension rod connected to the frame 199 and acting normally to draw the pulley frame upwardly and tighten the belt.

Referring to Figure 43, the spindle has mounted thereon an end plate 205, while the grinding wheel 20 includes a base flange 206 that is secured to said end plate by an attaching ring 207. It is important in this machine to provide for a continuous supply of a cooling liquid to the grinding wheel, and this is accomplished in the following manner.

The end plate 205 may be attached to the spindle through an intermediate collar 210 which is provided with an interior liquid chamber or conveyor 211, while 212 are 5 openings extending through the collar 210 and the plate 205 and leading to the interior of the grinding wheel. Suitable liquid conducting means is provided, including an outlet 213 entering the liquid conveyor 211, conducting pipe 214 and tube 215, see Figure 2, communicating with a liquid pump 216, to which the liquid is fed in any convenient way. The pump 216 is operated by a belt 217 leading to a pulley on the motor 10 shaft 91, see Figure 4.

The openings 212 are preferably arranged at an angle to the axis of the spindle 21, and as the grinding wheel and liquid conveyor rotate, the liquid is discharged forcibly through the openings 212 to the interior of the grinding wheel and outwardly toward its operating portions. In order to prevent the body of the grinding wheel from absorbing the liquid, its inner exposed surfaces 20 are coated with sulphur or other suitable substance, except at its operative portions, so that the cooling liquid is prevented from entering the body of the grinding wheel or 25 being absorbed thereby, and consequently 30 a maximum cooling effect on the operative portions of the grinding wheel is had.

Figures 44 to 46 illustrate a modified arrangement of the grinding wheel of smaller diameter than that of Figure 43. In the 35 last mentioned construction, the base flange 220 of the grinding wheel is in the path of the openings 221, and is cut away at 222 to permit passage of the cooling liquid. With this arrangement, the grinding wheel is 40 held in place by a ring 223, having portions 224 engaging the flange 220 of the grinding wheel at points intermediate the openings 222.

While the invention has been described 45 with reference more or less to a particular construction, it is not to be understood as restricted to any of the details or arrangements disclosed, since the application is intended to cover any modifications coming 50 within the intent of the invention or scope of the following claims. Subject to the limitations hereinbefore pointed out, the invention is also applicable to the cutting or 55 grinding of gear teeth which are either straight or curved lengthwise.

We claim:

1. In a machine for grinding curved tooth tapered gears, the combination with a 60 rotary annular grinding member having a cross-section conforming to a straight sided rack tooth and with unbroken tooth engaging grinding faces and blank support, of a bed on which the grinding member is mounted, said bed being intermittently movable away from the blank support to permit

indexing the blank, and automatic mechanism for imparting to the blank support a translatory movement and also a partial rotation about its axis whereby to roll the blank past the grinding member during operation 70 of the latter.

2. In a machine for grinding curved tooth tapered gears, the combination with a rotary annular grinding member having a cross-section conforming to a straight sided rack 75 tooth and with unbroken tooth engaging grinding faces and blank support, of a bed on which the grinding member is mounted, said bed being intermittently movable away from the blank support to permit indexing 80 the blank, a movable carrier for the blank support, a relatively stationary gear member, a second gear member fixedly connected to the blank support and adapted to roll on said stationary gear member, and means for automatically moving the carrier back and forth to roll the blank past the grinding member during operation of the latter.

3. In a machine for grinding curved tooth gears, the combination with a rotary annular grinding member and blank support, one movable toward and from the other to permit indexing, of automatic mechanism for imparting to the blank support a translatory movement and also a partial rotation about 95 its axis including a gear segment carried by the blank support and cooperating with a stationary gear segment whereby to roll the blank past the grinding member during operation of the latter.

4. In a machine for grinding spiral bevel gears, the combination with a rotary annular grinding member and blank support, one movable toward and from the other to permit indexing, of an oscillating carrier for the blank support, a relatively stationary gear member, a second gear member fixedly connected to the blank support and adapted to roll on said stationary gear member, and means for moving the carrier back and forth to roll the blank past the grinding member during operation of the latter.

5. In a machine for grinding curved tooth tapered gears, the combination with a rotary annular grinding member and blank support, one movable toward and from the other to permit indexing, a main drive controlling the aforesaid movements, dressing mechanism for the grinding member, and means controlled by said main drive and acting automatically to operate the dressing mechanism after a predetermined variable number of indexing operations of the blank.

6. In a machine for grinding curved tooth tapered gears, the combination with a rotary annular grinding member and blank support, one movable toward and from the other to permit indexing, means for imparting relative generating movement between the grinding member and blank support, a 125

main drive controlling the aforesaid movements, dressing mechanism for the grinding member, and means controlled by said main drive and acting automatically to operate the dressing mechanism after a predetermined variable number of indexing operations of the blank.

7. In a machine for grinding curved tooth tapered gears, the combination with a rotary 10 annular grinding member and blank support, automatic means for moving the grinding member away from the blank support to permit indexing, means for imparting to the blank support a translatory movement 15 and a rotation about its axis whereby to roll the blank past the grinding member during operation of the latter, a main drive controlling the aforesaid movements, dressing mechanism for the grinding member, and 20 means controlled by said main drive and acting automatically to operate the dressing mechanism after a predetermined variable number of indexing operations of the blank.

25 8. In a machine for grinding curved tooth tapered gears, the combination with a rotary annular grinding member and blank support, of a bed automatically movable away from the blank support to permit indexing, a support for the grinding member mounted on the bed, a main drive controlling the aforesaid movements, dressing mechanism for the grinding member, and means controlled by said main drive and acting 30 automatically to move the grinding member support on the bed a predetermined distance toward the blank support and automatically to operate the dressing mechanism after a predetermined variable number of tooth operations on the blank.

35 9. In a machine for grinding curved tooth tapered gears, the combination with a rotary annular grinding member and blank support, of a bed movable away from the blank support to permit indexing, automatic mechanism for imparting to the blank support a translatory movement and a partial rotation about its axis so as to roll the blank past the grinding member during the grinding 40 operation, a support for the grinding member movable on the bed, a main drive controlling the aforesaid movements, dressing mechanism for the grinding member, and means controlled by said main drive and acting automatically to advance said grinding member support on the bed toward the blank support and automatically to operate the dressing mechanism after a predetermined variable number of tooth operations on the blank.

45 10. In a machine for grinding curved tooth tapered gears, the combination with a grinding member and blank support, one movable toward and from the other to permit indexing, a main drive controlling move-

5 ment of the aforesaid elements, of mechanism controlled by said main drive and acting automatically to advance the grinding member with reference to the blank support and dress the grinding member after 70 a predetermined variable number of tooth operations.

11. In a machine for grinding curved tooth tapered gears, the combination with a grinding member and blank support, one movable 75 toward and from the other to permit indexing, a main drive controlling the aforesaid elements, mechanism controlled by said main drive and acting automatically to advance the grinding member with reference to the blank 80 support and to dress the grinding member after a predetermined variable number of tooth operations, and mechanism for automatically imparting a movement to the blank support so as to roll the blank past the 85 grinding member during operation of the latter.

12. In a machine for grinding curved tooth gears, the combination with a rotary annular grinding member and blank support, 90 of a carrier for the blank support automatically movable back and forth to impart a translatory movement to the blank, mechanism for rotating the blank support about its axis during said translatory movement 95 so as to roll the blank past the grinding member during operation of the latter, means for imparting a relative movement between the blank support and grinding member toward and from each other to permit indexing, a main drive controlling the aforesaid movements, and devices controlled by said main drive and acting automatically to advance the grinding member with reference to the blank support and to dress the 100 grinding member after a predetermined variable number of tooth operations.

13. In a machine for grinding curved tooth gears, the combination with a rotary annular grinding member and blank support, of 110 a carrier for the blank support automatically movable back and forth to impart a translatory movement to the blank, mechanism for rotating the blank support about its axis during said translatory movement so as to roll the blank past the grinding member during operation of the latter, a bed on which the grinding member is mounted, devices for intermittently moving the bed away from the blank support to permit indexing, a main drive controlling the aforesaid movements, and mechanism controlled by said main drive and acting automatically to advance the grinding member on the bed and to dress the grinding member after a predetermined variable number of tooth operations.

14. In a gear grinding machine, the combination with a grinding member and blank support, one movable toward and from the 130

- other to permit indexing, of a bed, a support for the grinding member movable on said bed, a screw operatively associated with the support for advancing the same on the bed, worm gearing for turning the screw, a main drive controlling the aforesaid movements, and means controlled by said main drive and acting automatically after a predetermined number of tooth operations to turn said worm gearing a predetermined amount.
15. In a gear grinding machine, the combination with a grinding member and blank support, one movable toward and from the other to permit indexing, of a bed, a support for the grinding member movable on said bed, a screw operatively associated with the support for advancing the same on the bed, and means acting automatically after a predetermined number of tooth operations to turn said screw comprising a shaft operatively connected with the screw, a ratchet wheel fixedly connected to the shaft, a pawl and pawl carrier for operating the ratchet wheel, an arm connected to the pawl carrier, and an intermittently moving cam controlling said arm.
20. In a gear grinding machine, the combination with a grinding member and blank support, one movable toward and from the other to permit indexing, of a bed, a support for the grinding member movable on said bed, a screw operatively associated with the support for advancing the same on the bed, worm gearing for turning the screw, a shaft on which the worm is mounted, a ratchet wheel fixedly connected to said shaft, a pawl and pawl carrier for operating the ratchet wheel, an arm connected to the pawl carrier, and a cam wheel acting at predetermined intervals to actuate said arm and advance the grinding member support.
25. In a machine for grinding curved tooth tapered gears, the combination with a rotary annular grinding member and blank support, one movable toward and from the other to permit indexing, of means for imparting a relative generating movement between the blank support and grinding member, a main drive controlling the aforesaid movements, and mechanism controlled by said main drive and acting automatically to advance the grinding member with reference to the blank support and dress the grinding member after a predetermined variable number of indexing operations.
30. In a machine for grinding curved tooth gears, the combination with a rotary annular grinding member and blank support, one movable toward and from the other to permit indexing, of a bed, a support for the grinding member movable on said bed, a screw operatively associated with the support for advancing the same on the bed, worm gearing for turning the screw, a shaft on which the worm is mounted, a ratchet wheel fixedly connected to said shaft, a pawl and pawl carrier for operating the ratchet wheel, an arm connected to the pawl carrier, and a cam wheel operating at predetermined intervals to move said arm.
35. In a machine for grinding curved tooth gears, the combination with a rotary annular grinding member and blank support, one movable toward and from the other to permit indexing, of means for imparting a relative generating movement between the blank support and grinding member, a main drive controlling the aforesaid movements, and mechanism controlled by said main drive and acting automatically to advance the grinding member with reference to the blank support and dress the grinding member after a predetermined variable number of indexing operations.
40. In a machine for grinding curved tooth gears, the combination with a rotary annular grinding member and blank support, one movable toward and from the other to permit indexing, of means for imparting a relative generating movement between the blank support and grinding member, a main drive controlling the aforesaid movements, and mechanism controlled by said main drive and acting automatically to advance the grinding member with reference to the blank support and operate the dressing
- on said bed, and mechanism acting automatically to advance the grinding member support on the bed after a predetermined number of tooth operations.
45. In a machine for grinding curved tooth gears, the combination with a rotary annular grinding member and blank support, one movable toward and from the other to permit indexing, of means for imparting a relative generating movement between the blank support and grinding member, a bed, a support for the grinding member movable on said bed, a screw operatively associated with the support for advancing the same on the bed, worm and worm gear mechanism for turning the screw, and means acting automatically after a predetermined number of tooth operations to turn said worm a predetermined amount.
50. In a machine for grinding curved tooth gears, the combination with a rotary annular grinding member and blank support, one movable toward and from the other to permit indexing, of means for imparting a relative generating movement between the blank support and grinding member, a bed, a support for the grinding member movable on said bed, a screw operatively associated with the support for advancing the same on the bed, and means acting automatically after a predetermined number of tooth operations to turn the screw comprising a shaft operatively connected with the screw, ratchet mechanism for said shaft, an arm controlling the ratchet mechanism, and a cam wheel operating at predetermined intervals to move said arm.
55. In a machine for grinding curved tooth gears, the combination with a rotary annular grinding member and blank support, one movable toward and from the other to permit indexing, of means for imparting a relative generating movement between the blank support and grinding member, a bed, a support for the grinding member movable on said bed, a screw operatively associated with the support for advancing the same on the bed, worm and worm gear mechanism for turning the screw, a shaft on which the worm is mounted, a ratchet wheel fixedly connected to said shaft, a pawl and pawl carrier for operating the ratchet wheel, an arm connected to the pawl carrier, and a cam wheel operating at predetermined intervals to control said arm.
60. In a curved tooth tapered gear grinding machine, the combination with a grinding member and blank support, one movable toward and from the other to permit indexing, dressing mechanism for the grinding member, a main drive controlling the aforesaid elements, and means controlled by said main drive and acting automatically to advance the grinding member with reference to the blank support and operate the dressing

mechanism after a predetermined variable number of operations of the grinding member on the blank.

23. In a curved tooth tapered gear grinding machine, the combination with a grinding member and blank support, one movable toward and from the other to permit indexing, dressing mechanism for the grinding member, a main drive controlling the aforesaid elements, means controlled by said main drive and acting automatically to advance the operating position of the grinding member with reference to the blank support and to operate the dressing mechanism after a predetermined variable number of operations of the grinding member on the blank, and devices for imparting a movement to the blank support so as to roll the blank past the grinding member during operation of the latter.

24. In a machine for grinding curved tooth tapered gears, the combination with a rotary annular grinding member and blank support, of a carrier for the blank support movable back and forth to impart a translatory movement to the blank, mechanism for rotating the blank support about its axis during said translatory movement so as to roll the blank past the grinding member during operation of the latter, means for imparting a relative movement between the blank support and grinding member toward and from each other to permit indexing, a main drive controlling the aforesaid movements, dressing mechanism for the grinding member, and devices controlled by said main drive and acting automatically to advance the operating position of the grinding member with reference to the blank support and operate the dressing mechanism after a predetermined variable number of operations of the grinding member on the blank.

25. In a machine for grinding curved tooth tapered gears, the combination with a rotary annular grinding member and blank support, one movable toward and from the other to permit indexing, means for imparting a relative generating movement between the blank support and grinding member, a bed, a support for the grinding member movable on the bed, a main drive controlling the aforesaid movements, dressing mechanism for the grinding member, and devices controlled by said main drive and acting automatically to advance the position of the grinding member on the bed and operate the dressing mechanism after a predetermined variable number of operations of the grinding member on the blank.

26. The combination with a gear blank support and tool mechanism, one movable toward and from the other to permit indexing, of automatic mechanism for effecting a relative withdrawal between the tool

mechanism and blank support to inoperative position after completion of a blank.

27. The combination with a gear blank support and tool mechanism, one movable toward and from the other to permit indexing, a cam controlling the last mentioned movement, and means for automatically changing the operative contour of the cam after completion of a blank, in order to effect withdrawal of such part to inoperative position to permit removal of the blank.

28. The combination with a gear blank support and tool mechanism, one movable toward and from the other to permit indexing, of a projection carried by said movable member, a cam cooperating with said projection, said cam including a movable switch device cooperating with the projection, and devices for automatically shifting said switch device after completion of a blank in order to withdraw the movable member to inoperative position and permit removal of the blank.

29. The combination with a gear blank support and tool mechanism, one movable toward and from the other to permit indexing, of a projection connected to the movable member, a cam cooperating with said projection, a switch device movably mounted on the cam and operating when in one position to effect withdrawal of the movable member to inoperative position to permit removal of the blank, and mechanism operating automatically to effect movement of said switch device upon completion of a blank.

30. The combination with a gear blank support and tool mechanism, one movable toward and from the other to permit indexing, of a projection connected to the movable member, a cam cooperating with said projection, a switch device movably mounted on the cam and operating when in one position to effect withdrawal of the movable member to inoperative position to permit removal of the blank, an oscillatory arbor on which said switch device is carried, a reciprocable rack cooperating with the arbor, a sleeve to which said rack is fixedly connected, weight-controlled means for effecting movement of the sleeve, and devices for automatically releasing said weight-controlled means upon completion of a blank.

31. The combination with a gear blank support and tool mechanism, one movable toward and from the other to permit indexing, of a projection connected to the movable member, a cam cooperating with said projection, a switch device movably mounted on the cam and operating when in one position to effect withdrawal of the movable member to inoperative position to permit removal of the blank, an oscillatory arbor on

which said switch device is carried, a reciprocable rack cooperating with the arbor, a sleeve to which said rack is fixedly connected, weight-controlled means for effecting movement of the sleeve, devices for automatically releasing said weight-controlled means upon completion of a blank, and means for automatically resetting the switch device and weight-controlled means.

32. The combination with a gear blank support and tool mechanism, one movable toward and from the other to permit indexing, automatic mechanism for stopping the machine and effecting a relative withdrawal between the tool mechanism and blank support to inoperative position to permit removal of a blank after its completion, and means governed by restarting the machine for automatically restoring the operative relationship between the tool mechanism and blank support.

33. The combination with a blank support and bed movable away from the blank support to permit indexing, tool mechanism mounted on the bed, of means acting automatically to stop the machine and withdraw the bed to inoperative position after completion of a blank, and mechanism controlled by restarting the machine and acting automatically to return the bed to operative position.

34. The combination with a gear blank support and tool mechanism, one movable toward and from the other to permit indexing, means for effecting a relative generating movement between the gear blank support and tool mechanism, of means acting automatically to stop the machine and effect a relative withdrawal of the blank support and tool mechanism after completion of a blank, and means controlled by restarting the machine and acting automatically to restore the operative relationship between the blank support and tool mechanism.

35. In a gear generating machine, the combination with a gear blank support and bed, one movable toward and from the other to permit indexing, of tool mechanism mounted on the bed, means for effecting a relative generating movement between the blank support and tool mechanism, of means acting automatically to stop the machine and withdraw the bed to inoperative position to permit removal of a blank after its completion, and mechanism controlled by restarting the machine and acting automatically to restore the bed to operative position.

36. The combination with a gear blank support and tool mechanism, one movable toward and from the other to permit indexing, a cam controlling the last mentioned movement, means for automatically stopping the machine and changing the operation of the cam after completion of a blank, and devices controlled by restarting the machine and act-

ing automatically to restore said cam to its normal operation.

37. The combination with a gear blank support and tool mechanism, one movable toward and from the other to permit indexing, of a projection carried by the movable member, a cam cooperating with said projection, said cam including a movable switch device cooperating with the projection, devices for automatically stopping the machine and shifting said switch device after completion of a blank, and means governed by restarting the machine and acting automatically to restore the switch device to normal position.

38. The combination with a gear blank support and tool mechanism, one movable toward and from the other to permit indexing, of a projection carried by the movable member, a cam cooperating with the projection, a switch device movably mounted on the cam and operating when in one position to effect withdrawal of the movable member to inoperative position to permit removal of a blank, an oscillatory arbor on which the switch device is carried, a reciprocable rack cooperating with the arbor, a sleeve to which said rack is fixedly connected, weight-controlled means for effecting movement of the sleeve, an electric motor for operating the machine, a switch controlling the motor, means for automatically operating said switch to stop the motor upon completion of a blank and simultaneously releasing said weight, and devices controlled automatically by restarting the motor for resetting the weight and motor switch.

39. The combination with a gear blank support and tool mechanism, one movable toward and from the other to permit indexing, of a projection carried by the movable member, a cam cooperating with the projection, a switch device movably mounted on the cam and operating when in one position to effect withdrawal of the movable member to inoperative position to permit removal of a blank, an oscillatory arbor on which the switch device is carried, a reciprocable rack cooperating with the arbor, a sleeve to which said rack is fixedly connected, weight-controlled means for effecting movement of the sleeve, an electric motor for operating the machine, a switch controlling said motor, means for automatically operating said switch to stop the motor upon completion of a blank and simultaneously releasing said weight, devices controlled automatically by restarting the motor for resetting the weight and motor switch.

40. The combination with a gear blank support and tool mechanism, one movable toward and from the other to permit indexing, a cam controlling the last mentioned movement, means for automatically stopping the machine and changing the operation of the cam after completion of a blank, and devices controlled by restarting the machine and act-

and cooperating with said switch and weight, a pawl movable with the controlling device and cooperating with the ratchet wheel normally to prevent return movement of the latter, a locking member cooperating with the controlling device and operating to hold said pawl disengaged from the ratchet wheel to permit return of the latter to normal position, and resetting means operating automatically to release the locking member upon restarting the machine and permit return of the parts to normal position.

40. In a gear generating machine, the combination with a gear blank support and tool mechanism, of means for effecting a relative generating movement between said parts including an oscillatory segment connected to one of said parts and a relatively stationary segment on which the oscillatory segment rolls, said stationary segment including a plurality of yieldable sections.

41. In a gear generating machine, the combination with a gear blank support and tool mechanism, of means for effecting a relative generating movement between said parts including an oscillatory segment connected to one of said parts and a relatively stationary segment for turning the oscillatory segment, said stationary segment including a plurality of toothed segmental sections, a slide on which each section is mounted, a guide for the slide, and spring means for maintaining the slide in normal position and permitting yielding thereof.

42. In a gear grinding machine, the combination with a blank support and an annular rotary grinding member, of means for effecting a relative generating movement between said parts including an oscillatory segment connected to one of said parts and a relatively stationary segment on which the oscillatory segment rolls, said stationary segment including a plurality of yieldable sections.

43. In a gear grinding machine, the combination with a blank support and an annular rotary grinding member, of means for effecting a relative generating movement between said parts including an oscillatory segment connected to one of said parts, and a relatively stationary segment for turning the oscillatory segment, said stationary seg-

ment including a plurality of toothed segmental sections, each section being mounted on a slide at its central part, a guide for the slide, and spring means for maintaining the slide in normal position and permitting yielding thereof.

44. The combination with a gear blank support and tool mechanism, of index mechanism including an index wheel fixed to the blank support, a movable lever, a locking dog carried by said lever and operating to lock and unlock the index wheel, and means for adjusting the blank support with reference to the index mechanism comprising instrumentalities for adjusting said locking dog on the movable lever while the dog is engaged with the index wheel.

45. The combination with a gear blank support and tool mechanism, of index mechanism including an index wheel fixed to the blank support, a locking device cooperating with the index wheel, and mechanism for adjusting the locking device and index wheel with reference to the other parts of the index mechanism so as to change the relative position of the blank support.

46. The combination with a gear blank support and tool mechanism, of indexing mechanism including an index wheel fixed to the blank support, a movable lever, a locking dog carried by said movable lever and operable to lock and unlock the index wheel, said dog being carried by a slide adjustable upon the movable lever, and means for changing the position of said slide and dog upon the lever while it is engaged with the index wheel in order to adjust the blank with reference to the index mechanism.

47. In a machine for grinding spiral bevel gears, the combination with a gear blank support and a rotary annular grinding member, one movable toward and from the other to permit indexing, of mechanism acting automatically to effect a relative withdrawal between the tool and blank support to inoperative position after completion of a blank.

In witness whereof, we have hereunto signed our names.

EDWARD W. BULLOCK.
ALTON P. SLADE.
